[57] CLAIM

The ornamental design for a polygon shaped hair ornament storage ring, as shown and described.

DESCRIPTION

FIG. 1 is a perspective view of a polygon shaped hair ornament storage ring, showing my new design;
FIG. 2 is a front elevational view thereof;
FIG. 3 is a top plan view thereof;
FIG. 4 is a rear elevational view thereof;
FIG. 5 is a bottom plan view thereof; and,
FIG. 6 is a sectional view taken along line 6—6 in FIG. 4.
The broken line environmental structure is for illustrative purposes only and forms no part of the claimed design.
